PATENTED JULY 10, 1906.

P. P. BROOKS.

AUTOMATIC CYLINDER DRAIN VALVE.

APPLICATION FILED AUG. 16, 1905.

UNITED STATES PATENT OFFICE.

POSEY PERCY BROOKS, OF HATTIESBURG, MISSISSIPPI.

AUTOMATIC CYLINDER DRAIN-VALVE.

No. 825,513.

Specification of Letters Patent.

Patented July 10, 1906.

Application filed August 16, 1905, Serial No. 274,456.

To all whom it may concern:

Be it known that I, Posey Percy Brooks, a citizen of the United States, residing at Hattiesburg, in the county of Perry and State of Mississippi, have invented a new and useful Automatic Cylinder Drain-Valve, of which the following is a specification.

The invention relates to improvements in cylinder drain-valves.

10 The object of the present invention is to improve the construction of cylinder drain-valves and to provide an automatic valve designed for use on the cylinders of locomotives, pumps, and the like and adapted to enable the water resulting from the condensation of steam to be readily ejected when desired.

A further object of the invention is to provide an automatic drain-valve adapted to be maintained in a closed position by fluid-pressure under the control of an engineer and capable of opening automatically to permit the escape of steam and water when the pressure is reduced by the engineer.

25 With these and other objects in view the invention consists in the construction and novel combination and arrangement of parts, hereinafter fully described, illustrated in the accompanying drawings, and pointed out in 30 the claims hereto appended, it being understood that various changes in the form, proportion, size, and minor details of construction within the scope of the claims may be resorted to without departing from the spirit 35 or sacrificing any of the advantages of the invention.

In the drawings, Figure 1 is a side elevation of a locomotive provided with a cylinder drain-valve constructed in accordance 40 with this invention. Fig. 2 is a reverse plan view illustrating the arrangement of the automatic drain-valves at the ends of two locomotive-cylinders. Fig. 3 is an enlarged side elevation of the automatic drain-valve. Fig. 4 is a longitudinal sectional view of the same. Fig. 5 is a sectional view on the line 5-5 of Fig. 4.

Like numerals of reference designate corresponding parts in all the figures of the 50 drawings.

1 designates the automatic drain-valve body, designed to be constructed of brass or other suitable material and provided at the top with a tubular extension 2, forming a lateral steam inlet or passage for the escape of

steam and water from the cylinder 4 of a locomotive. The valve-body is cylindrical, and the inlet 3 is turned and chased to fit any size cylinder-opening. The valve-body is provided with a removable bonnet 5, and its front or outer end 6 is interiorly threaded to receive exterior threads 7 of the bonnet 5, which is provided with a flange 6 to fit against the front edge of the bonnet and which has a polygonal wrench-receiving face 7, adjacent to the flange 6, to enable it to be readily screwed into and out of the valve-body. The bonnet, which constitutes the front of the valve casing or body, is counterbored to provide an interior shoulder 8, and it has a beveled valve-seat 9 at its inner end to receive a winged valve 10, the wings 11 terminating short of the shoulder 8 when the valve is seated, as illustrated in Fig. 4 of the drawings.

The valve is provided at its rear end with a piston-head 12, which is arranged within the rear portion of the valve-body and which is spaced from the beveled engaging portion of the valve by a cylindrical intermediate 80 portion 13, which is provided to afford sufficient stock to enable the valve to be ground down from time to time to fit the seat properly. The rear portion 14 of the body or casing of the valve constitutes a piston-chamber 85 and the piston-head, which is adapted to slide in the chamber 14, is provided with a pair of packing-rings 15, seated in grooves and adapted to be employed when air is used for maintaining the valve normally on its 90 seat. The packing-rings may be provided when steam is employed, as shown in the accompanying drawings, but can be omitted, if desired. The rear or piston end of the valve is provided with a threaded socket 16, 95 adapted to enable it to be connected with a tool for grinding the valve into the seat.

The rear or inner end of the body or casing of the valve is provided with a threaded aperture 17, which forms a rear inlet for the admission of fluid-pressure, and the automatic drain-valves of each cylinder of the locomotive are connected by a transverse pipe or tube 18, composed of sections coupled by a union, as clearly shown in Fig. 2 of the drawings. The pipes 18 are connected at their rear ends by a transverse pipe or tube 19, which is provided with a central coupling and is connected by a steam-pipe 20, which extends along the locomotive from the front 110

to the rear portion thereof to a three-way valve 21, located in the cab of the locomotive. The three-way valve is connected by a pipe 22 with the main steam-tube of the boiler 23 of the locomotive, which is tapped at a suitable point. The three-way valve is also provided with an exhaust-pipe 24, which extends downward and which discharges exteriorly of the cab. As the boiler-pressure is in excess of cylinder-pressure, and also as the diameter of the piston-head is in excess of that of the valve-face, the valve will remain firmly seated when there is a constant pressure against the piston-head. When it is desired to drain the cylinders of the locomotive, the three-way cock is operated to cut off the supply of steam and to connect the pipe or tube 20 with the exhaust-pipe for reducing the pressure in rear of the valves. The front face of the enlarged rear or piston-head portion of the valve is slightly curved to form a semisteam groove, the face 13 of which is of less area than the piston-head, and the cylinder-pressure operating against the said face 13 will move the valve rearward, thereby permitting the steam and water of condensation to blow out through the outlet opening or passage of the bonnet of the valve. The pipe 22 may be connected with any other suitable source of fluid-pressure—as, for instance, the main air-drum or any other portion of the air-brake system—and the three-way valve will enable such pressure to be controlled for holding the automatic valve on its seat and for reducing the pressure in rear thereof to permit an automatic operation of the valve to drain the cylinder.

The pipes or tubes 18 and 19, which connect the automatic drain-valves, may, if desired, be provided with a drain valve or cock for preventing water from accumulating and freezing therein and to enable any water to be discharged from them.

It will be seen that the drain-valve is automatic in its opening operation, and that as soon as the rear piston-head is relieved of pressure it will automatically open and permit a discharge of steam from the cylinder and a consequent ejection of water accumulating in that end of the cylinder. Furthermore, it will be apparent that as soon as pressure is applied to the piston-head the seat-engaging portion or valve proper will be carried into engagement with the valve-seat, and the outlet will be closed to prevent an escape of the steam. Also it will be apparent that the main valve is applicable to various forms of pumps and cylinders and that it will prevent injury resulting from accumulation of water in them.

Having thus fully described my invention, what I claim as new, and desire to secure by Letters Patent, is—

65 1. An automatic drain-cock comprising a

casing provided at the front with an outlet and having a lateral inlet at an intermediate point for connection with a steam-cylinder, said casing being also provided in rear of the lateral inlet with a piston-head chamber and having a rear inlet-port for the admission of fluid-pressure, a valve-seat located in advance of the lateral inlet, and a valve coöperating with the seat and provided with a piston-head operating in the said chamber in rear of the lateral inlet, said valve being also provided at an intermediate point with a face of less area than the piston-head and located at the lateral inlet, whereby it is subjected to constant cylinder-pressure.

2. An automatic drain-valve comprising a casing having a lateral inlet and provided in rear of the same with a piston-head chamber and having a rear inlet-port for the admission of fluid-pressure, a valve-seat arranged in advance of the lateral inlet, and a valve coöperating with the seat and provided with a piston-head operating in the said chamber, said piston-head being of greater diameter than the valve and provided at its front with a partial steam-groove exposed at the lateral inlet.

3. An automatic drain-valve comprising a casing having a lateral inlet and provided in rear of the same with a piston-head chamber and having a rear inlet for the admission of fluid-pressure, a valve-seat arranged in advance of the lateral inlet, and a valve having a front seat-engaging portion and provided with a rear piston-head operating in the said chamber in rear of the lateral inlet and provided at its front with a partial steam-groove exposed at the said lateral inlet, said valve being also provided with an intermediate connecting portion located between the steam-groove and the seat-engaging portion.

4. An automatic drain-valve comprising a casing having a lateral inlet and provided in rear of the same with a piston-head chamber and having a rear inlet-port for the admission of fluid-pressure, a valve-bonnet secured to the casing in advance of the lateral inlet and provided with a valve-seat, said bonnet being also provided with an interiorly-arranged shoulder, and a winged valve having a seat-engaging portion and provided in rear of the lateral inlet with a piston-head, the wings of the valve extending into the bonnet and terminating short of the said shoulder.

5. An automatic drain-valve comprising a casing having a lateral inlet and provided in rear of the same with a piston-head chamber and having a rear inlet-port for the admission of fluid-pressure, a separate valve-bonnet secured to the front of the casing in advance of the inlet and provided with a valve-seat and having a front outlet, and a valve coöperating with the valve-seat and provided with a piston-head operating in said chamber in rear of the lateral inlet, said

valve being also provided at an intermediate point with a face of less area than the piston-head and located at the lateral inlet, and the said outlet being located in front of the valve and at a point opposite the rear inlet, which is located back of the piston-head.

In testimony that I claim the foregoing as

my own I have hereto affixed my signature in the presence of two witnesses.

POSEY PERCY BROOKS.
